(57) **CLAIM**

We claim the ornamental design for an audio cable connector with plated tip, as shown and described.

DESCRIPTION

FIG. 1 is a left-front perspective view of an audio cable connector with plated tip;

FIG. 2 is a top plan view of FIG. 1;

FIG. 3 is a bottom plan view of FIG. 1;

FIG. 4 is a front elevation of FIG. 1;

FIG. 5 is a rear elevation of FIG. 1;

FIG. 6 is a left side elevation of FIG. 1; and,

FIG. 7 is a right side elevation of FIG. 1.

The broken lines in the drawing are included for illustrative purposes only and form no part of the claimed design.
